UNITED STATES PATENT OFFICE.

MICHAEL J. FERON, OF CHICAGO, ILLINOIS.

BLOCK-SIGNAL.

No. 912,103.

Specification of Letters Patent.

Patented Feb. 9, 1909.

Application filed September 19, 1908. Serial No. 453,716.

To all whom it may concern:

Be it known that I, MICHAEL J. FERON, a citizen of the United States, residing at Chicago, in the county of Cook and State of Illinois, have invented a new and useful Improvement in Block-Signals, of which the following is a specification.

My invention is in the nature of a novel and improved automatic block-signal system for use upon elevated railways, surface trolley-lines, etc.; my object being to provide a simple and effective means for safeguarding, more especially, against rear-end collisions.

In carrying out my invention I provide a series of visual signals, such as targets, lamps, or the like, placed at predetermined distances apart along the railway-track and each in such relation with reference thereto that it will be obscured by a passing train from the view of the motorman, or driver, of a following train when the latter approaches the former too closely under the rules.

In the drawing—Figure 1 is a diagrammatic illustration of a double-track railway equipped with my improved signaling system; Fig. 2, a similar view at a curve in the tracks; and Figs. 3 and 4, face and edge views, respectively, of a combined target and light signal such as I prefer to employ.

5 and 6 are railway-tracks; 7 and 8 station-platforms; and 9 and 10 trains. The trains indicated run in the direction designated by the arrow. In other words, they move upon the right-hand track. The track 6 is for trains running in the opposite direction. It is to be understood, furthermore, that the motorman's or driver's compartment is at the right-hand side of the forward end of each train.

Located at predetermined distances apart between the tracks 5, 6 are signals 11 which may be constructed as illustrated in Figs. 3 and 4. Each consists of a standard or post 12 having a slot in its upper end-portion to receive a square board or plate 13 in the manner indicated. In practice, the post 12 and board 13 may be painted white, and a black bull's-eye 14 painted or otherwise provided in the position shown. Below the bull's-eye is an opening 15 through the post to receive an incandescent electric-lamp 16. The target answers as a day-signal and the light as a fog or night-signal. In practice, the targets or signals are about four feet in height so that the bull's-eyes 14 are some-

what above the level of the floors of the cars of passing trains.

Presuming, for example, that the rules governing the running of trains on the track 60 illustrated in Fig. 1 forbid the approach of a train nearer than, say, 300 feet from the rear end of a train ahead, the signals 11 may be placed, say, 400 feet apart. The signals are located close to the tracks in a manner 65 merely to be safely cleared by the trains. The motorman's position on the second train, 9, is at 17, and the rules make it necessary for him to keep in view say at least one signal ahead. Fig. 1 shows that the train 9 has approached the rear end of train 10 as closely as the rules governing the running of trains on this section permit. The motorman on train 9 is about to pass a signal 11 and his vision of the next signal 11 is along the 75 dotted line 18. Any nearer approach to the rear end of train 10 would have caused the latter to obscure the said signal from the view of the motorman of train 9, and it would at once become apparent to him that 70 he has approached the train ahead too closely. On curves, as indicated in Fig. 2, the signals may be placed more closely together, so that one, at least, may always be in sight of the motorman of an approaching 85 train. The rules usually provide that a motorman shall move his train more slowly on curves than on straight tracks, so that on curves a train may, without danger, approach a train ahead more closely than upon 90 straight tracks, thus permitting the signals 11 to be placed nearer together.

In the system illustrated the signals placed between tracks answer for trains running in both directions. In a system where- 95 in trains run upon the left-hand, instead of the right-hand, track, and the motorman's position is the same as herein shown, namely, at the right-hand side of the front of the train, the signals 11 would be placed at the 100 outer sides of the tracks instead of between them. Where necessary, or desirable, the signals 11 may be suspended from overhead supports instead of being mounted on stand- 105 ards, as described. It is to be understood 105 that, in practice, various contingencies would govern the distances at which signals are spaced apart on different sections of a railway. For example, where the rules pre- 110 scribe comparatively slow running-time, they may be placed a comparatively short distance apart, while where the rules de-

mand faster running of the trains the signals may be placed farther apart, or the rules may demand that the motorman keep at least two signals in sight at all times.

5 One reason why a signaling system like the present is desirable, particularly on elevated railways, is due to the fact that many motormen are unable to measure distances with the eye with any degree of accuracy. Therefore, when traffic demands that trains be run at intervals as frequent as safety may permit, the too near approach of one train behind another not infrequently, when, for example, one train is obliged to stop suddenly, results in the collision with it of the following train through the motorman's inability to stop the latter in time. A system of this kind, furthermore, makes it easy for an inspector, or other official, to note whether 10 or not motormen are obeying the rules with regard to approaching trains ahead too closely. The present system makes it possible to establish rules regarding the running of trains with safety where, without the 15 system, such rules could not be followed by motormen with necessary certainty. For example, on an electric railway the current provided is usually insufficient to permit more than a certain number of trains to 20 start up at the same time. By establishing a rule that in case of congestion, or after a blockade, no train shall start until the train ahead has passed beyond the signal ahead this difficulty may be safeguarded without 25 over-reliance upon the judgment of the motormen.

It is to be understood that my improved block-signal system may be modified as de-

sired to meet special requirements without departing from the spirit of my invention as 40 defined by the claims.

What I claim as new and desire to secure by Letters Patent, is—

1. In a block-signal system for railways, a series of signals placed at predetermined 45 distances apart along the track and each located with reference to the track to be obscured by a passing train from view from the motorman's position on a following train approaching with too near proximity 50 of the first-named train, for the purpose set forth.

2. In a block-signal system for railways, a series of signals placed at predetermined distances apart along one side of and close to 55 the track, and each in a plane above that of floors and beneath that of roofs of the cars, to be obscured by a passing train from view from the motorman's position on a following train approaching with too near proximity 60 to said first-named train, for the purpose set forth.

3. In a block-signal system for railways, a series of combined target and lamp signals placed at predetermined distances apart 65 along the track and each located with reference to the track to be obscured by a passing train from view from the motorman's position on a following train approaching with too near proximity 70 of the first-named train, for the purpose set forth.

MICHAEL J. FERON.
